JOHN F. METTEN, OF PHILADELPHIA, PENNSYLVANIA

CRUISING-TURBINE ARRANGEMENT

Application filed March 15, 1926. Serial No. 94,976.

This invention relates to ship propulsion mechanism and more particularly to an apparatus and method of driving auxiliaries such as air and feed pumps, lubricating 5 pumps, etc.

An object of my invention is to provide an improved arrangement of turbines and controls for driving auxiliaries employed in connection with marine propulsion machinery. 10 A more specific object is to drive the auxiliaries by a cruising turbine and to provide suitable controls whereby the cruising turbine may be operated in series with the main turbines or independently thereof. Another 15 object is to provide automatic features for facilitating the changing of the mode of operation. Other objects will appear from the following description of the accompanying drawing, in which

20 Fig. 1 is a diagrammatic view of the propelling machinery and auxiliaries, and Fig. 2 is a side elevation of certain of the auxiliary pumps.

25 Fig. 3 is a diagrammatic view showing a modified arrangement involving supplemental turbine auxiliaries.

Fig. 4 is a diagrammatic view showing one form of mechanical means for co-ordinating the valve.

30 Fig. 4^a is a fragmentary face view of a valve interlock. Figs. 5, 6 and 7 are views illustrating the speed governor for controlling the independent steam supply of the cruising turbine, together with associate 35 parts; Fig. 5 being an end view of the speed governor and associate parts drawn to an enlarged scale; and Figs. 6 and 7 being respectively sectional views on the line 6-6 and 40 7-7 of Fig. 5.

45 Figs. 8 and 9 are views diagrammatic in character and illustrating different settings of the valve system.

Prior art constructions have utilized a 50 cruising turbine, clutch connected through a suitable gear train to main turbine units to drive the propeller shaft, which combination has proved very desirable on high powdered vessels for operating at reduced speeds on account of the greatly decreased steam con-

sumption of the propelling unit at low powers.

As adjuncts of all propelling turbines, there is a group of auxiliaries that must be in operation during all times when the propelling units are in use. These are the above 55 enumerated pumps and others which are usually independent units, each driven by its own steam cylinder, turbine or motor, as the case may be. The capacity at which these auxiliaries are required to operate bears certain 60 relations to the power developed by the main units, but does not decrease in the same proportion. Necessarily these must have individually the capacities fixed by full 65 power conditions, and at greatly reduced powers these auxiliaries work very much below their capacity but without proportional reduction in their steam consumption. This results in a very serious impairment of the 70 economy of the plant as a whole at low fractional powers. At full powers the auxiliaries coordinated with the operation of the main turbines may require a steam consumption 75 of only 5% or 6% of that used in the main turbines. At one-twentieth of full power the consumption of these auxiliaries may be as much as 30% or 40% of the total consumption owing to the fact that their duty does not fall off in direct proportion and the steam 80 consumption in relation to the work done increases rapidly with reduced capacities.

In order to overcome this condition I provide an improved arrangement whereby the auxiliaries which are required to be in operation during operation of the main propelling units can be driven by the geared cruising turbine either independently of the main propelling turbine, or connected to the same. The connection or disconnection of the cruising 85 turbine will be controlled by the requirement to effect the desired improvement in overall steam consumption at all powers, and particularly at reduced speed and 90 powers.

In Fig. 1 there is shown a cruising turbine 1, connected to a high pressure turbine 2, as through usual cruising turbine reduction gearing generally indicated 3, and a clutch 4 95 which is preferably hydraulically actuated in

a manner such as disclosed in Patent No. 1,047,908. A low pressure main turbine unit 5 cooperates as through suitable reduction gearing 6 to drive a propeller shaft 7. Leading from a steam supply pipe 8 is a cruising turbine supply pipe 9 which is controlled by a valve 10. This pipe is used when the cruising turbine is run in series with the main turbines. When the cruising turbine is run independently thereof a small independent pipe 11 supplies steam to a separate nozzle on the cruising turbine through a speed governor controlled valve 11', the governor for which is usually mounted on the cruising turbine spindle and is responsive to speed variations thereof. This feature will be understood from a consideration of Figs. 5-7, wherein the cruising turbine spindle indicated at 1^a carries a ball governor 1^b of ordinary type which is effective through connections comprising bell crank 1^c, slide rod 1^d, lever 1^e and slide rod 1^f on the valve 11'. The valve proper as herein shown is a double disc or cage type of double balanced valve known as a throttling governor valve. A small independent exhaust pipe 12 leads from the cruising turbine to an auxiliary exhaust line 13, controlled by an automatic back pressure valve 14. The pipe 13 may be connected to a condenser if desired. The exhaust pipe 12 functions when steam is supplied through the independent pipe 11 and exhaust pipe 21 functions when steam is supplied through pipe 9, as shown respectively in Figs. 8 and 9. To operate the main turbines independently of the cruising turbine, a supply pipe 15 leads from pipe 8 to the high pressure turbine 2, fluid flow being controlled by a valve 16. Exhaust from the high pressure turbine is conducted as by a pipe 17 to the low pressure turbine 5 from which exhaust is conducted to a usual condenser 18. When the main turbines are independently operated valve 10 is closed and valve 16 opened (Fig. 8). A non-return valve 20 is interposed in the cruising turbine exhaust line 21 leading from the cruising turbine to the line 15. When valve 16 is opened steam will automatically close the valve 20 thereby shutting off exhaust communication through pipe 21 from turbine 1. Valves 10 and 16 are preferably interlocked in a manner such as disclosed in my Patent No. 1,214,207, so that either valve must be closed before the other can be opened. The valve interlocking means is fragmentarily illustrated in Fig. 4^a and comprises a slide bar 16^a provided with key hole slots suitably formed and disposed for cooperation with the valve stems and their hubs or enlargements. As illustrated the upper slot having its narrow part in register with the valve stem of the valve 10 will obstruct the outward movement of the hub of said valve stem so long as the hub of the stem of valve 16 is in register as shown with

the enlarged portion of its key hole slot. If valve 10' is open exhaust will take place from the cruising turbine through pipe 12, this diverting of the exhaust steam being automatic upon closure of valve 20.

The before-mentioned auxiliaries consist, among other possible ones, of air pumps having cylinders 25 connected to the condenser as by a pipe 26, these pumps being adapted for drawing air and condensate from the main condenser 18, a plunger pump having cylinders 27 disposed on opposite sides of each of the air pump cylinders 25, which pumps 27 are principally for the purpose of pumping condenser water while a pump 28, preferably of the centrifugal type, is provided for circulating lubricating oil.

The plungers for the pumps 27 may be actuated by cross heads 30 connected to a crank pin 31 which is carried upon a transverse shaft 32. The shaft 32 is driven from the cruising turbine by a shaft 33 connected to the turbine through the gear train 3 and by a worm and gear connection disposed in a housing 34, the worm gear being carried by shaft 32 while the worm is carried on the shaft 33. The pumps 25 are also actuated by the crank pins 31 due to the piston rods 35 being connected to the cross heads 30. The lubrication pump is driven by a shaft 36 connected to shaft 33 through bevel gears 37. Various other forms of pumps may be used depending upon the particular installation.

The operation is as follows:—assuming, for example, that the main turbines alone are in operation for say from one-eighth to full power and the clutch 4 is disconnected. The group of auxiliary pumps above enumerated can now be operated by the cruising turbine through the gear mechanism 3 independently of the main units. This operation can be effected economically as the cruising unit is a high efficiency high speed unit. The cruising unit would not otherwise be in use under this range of power of the main turbines. During this operation valve 10 will be closed and valves 16 and 10' opened. Steam pressure in line 15 will accordingly close non-return valve 20 and exhaust steam from the cruising turbine will pass out through exhaust pipe 12 and valve 14. The valves 14 and 20 are coordinated by any usual mechanical or pressure operated means such as shown in Fig. 4 so that when one opens the other closes and vice versa. As shown in Fig. 4 the valves 20 and 14 are connected by a leverage system comprising a bell crank 20^a having one of its arms connected to the valve proper and its other arm to one end of a link 20^b. The opposite end of said link is in turn connected to the longer arm of a bell crank 14^a, the shorter arm of said bell crank being connected to the valve proper of the valve device 14. This connection provides for the alternate working of the two valves 14 and 20 au-

tomatically. The automatic control may comprise a spring 22 which is effective to maintain the valve 14 normally open, the tension of this spring being overcome when the back pressure of the steam acting on the valve 20 is sufficiently high, as will result from operating with cruising throttle open as shown in Fig. 9. When operating under the conditions shown in Fig. 8 the pipe 15 is under high pressure which acting on the disc of valve 20 augments the pull of the spring and keeps valve 20 closed and the valve 14 open. Preferably associated with the valve 20 is a hand-wheel 23 having a threaded stem and which is arranged to hold the valve 20 closed when operating the cruising turbine for driving the auxiliaries as shown in Fig. 8, the main turbine system being idle and the valve 16 closed at this time. With the valve 10' opened the steam supply is controlled preferably by the governor mechanism 11' although if desired the governor may be omitted and the steam supply controlled entirely by the valve 10'. The power generated by the cruising turbine will be sufficient to actuate all of the auxiliaries and to do so under efficient operation even though the main turbines may be running at only part load.

For operation of the cruising unit in series with the main turbine units, the clutch 4 is engaged and steam supplied through the cruising throttle 10, the valve 16 being closed under this condition. Steam exhausted from the cruising turbine will pass through exhaust pipe 21 and open the non-return valve 20 so as to flow through pipe 15 to the high pressure main turbine unit 2, from whence it flows to pipe 17 to the low pressure turbine unit 5. The condensate and air is pumped from the condenser 18 through pipe 26 to the air pumps. Under this condition the power required to drive the auxiliary pumps is obtained at the combined water rate of the cruising turbine and main turbines or at about one-fifth of the steam that would be required to operate these units from independent turbines or steam cylinders. The change over from this method of operation to higher powers from the main turbines is effected by shutting off the cruising throttle 10 and releasing the clutch 4, also opening valve 16. This allows the cruising turbine and connected auxiliaries to continue in operation without stopping under the small auxiliary steam supply through pipe 11, the auxiliary valve 10' preferably being left open at all times except when the entire plant is shut down. If operating under the main units independently and it is desired to reduce speed and operate with the cruising unit connected, all that is necessary is to reduce the speed of the main units to that of the cruising unit, then connect clutch 4 and open cruising throttle 10.

It will thus be seen that from my improved

arrangements of parts exhaust steam from the cruising turbine is automatically taken care of regardless of whether the same is operating in series with the main units or independently thereof. It will also be clear that if desired the auxiliaries adapted to be driven by the cruising turbine may be of a capacity below that required for full power condition, these auxiliaries then being supplemented by independent auxiliaries which would be shut down when the ship is operated within range of the cruising combination. Independent clutches for the several auxiliaries could be provided, as would be deemed necessary. For example, as shown in Fig. 3, an independent turbine 45 drives supplementary mechanisms 28', 25' and 27', corresponding respectively to mechanisms 28, 25 and 27. These mechanisms may be operated independently of each other, or simultaneously by use of clutches 46 and 47 adapted to control power flow from the turbine shaft 48 to the respective mechanisms. These pumps may be connected to the main lines such as 26, and the pipe which would be used in connection with pump 28. These supplemental connections are shown at 26' and 49. In operation, the units 28, 25 and 27 would be sufficient to take care of the cruising conditions, but when full power or power above a predetermined point is developed by the main turbines, independent turbine 45 will be operated to actuate the supplemental auxiliary turbine mechanisms, these, in connection with the other auxiliary mechanisms, being of sufficient capacity for full power conditions. A pipe 40 is adapted to conduct steam from the supply pipe 8 through valve mechanism 41 to the reversing blades on the low pressure turbine unit 5.

I claim:

1. The combination comprising a main turbine, a cruising turbine, means whereby said cruising turbine may mechanically operate in series with or independently of said main turbine, turbine auxiliary mechanisms, and means for driving said auxiliaries from said cruising turbine.
2. The combination comprising a main turbine, a cruising turbine, means whereby said cruising turbine may mechanically operate in series with or independently of said main turbine, turbine auxiliary mechanisms, means for driving said auxiliaries from said cruising turbine, and means for supplying steam to said cruising turbine at a rate less than normally required for cruising operation when said cruising turbine is operated independently.
3. The combination comprising a main turbine, a cruising turbine, means whereby said cruising turbine may mechanically operate in series with or independently of said main turbine, turbine auxiliary mechanisms, means for driving said auxiliaries from said cruis-

ing turbine, and means for supplying steam to said cruising turbine when mechanically operating in series with the main turbine.

4. The combination comprising a main 5 turbine, a cruising turbine, means whereby said cruising turbine may mechanically operate in series with or independently of said main turbine, turbine auxiliary mechanisms, means for driving said auxiliaries from said 10 cruising turbine, and means for conducting exhaust steam from said cruising turbine to said main turbine.

5. The combination with a cruising turbine, of a normal steam supply means therefor, a supplemental steam supply, means for controlling said supplemental supply by speed governing mechanism associated with said turbine, an exhaust pipe adapted for co-operation with the normal supply, an exhaust 20 pipe adapted for cooperation with the supplemental supply, and means for shutting off said normal supply while said supplemental supply continues.

6. The combination with a cruising turbine, of a normal steam supply means therefor, a supplemental steam supply, means for controlling said supplemental supply by governing mechanism, an exhaust pipe adapted for cooperation with the normal supply, an 30 exhaust pipe adapted for cooperation with the supplemental supply, means for shutting off said normal supply while said supplemental supply continues, and means whereby said normal exhaust pipe is automatically rendered inoperative when said normal supply is cut off, thereby permitting the supplemental exhaust to operate.

7. The combination with a cruising turbine unit, of a main turbine unit, normal 40 and supplemental means for supplying steam to said cruising unit, means for conducting the exhaust of said normal supply to the main unit, means whereby steam may be supplied to the main unit without passing 45 through the cruising unit and while the supplemental steam supply to the latter is maintained, said normal exhaust and main unit steam supply pipes merging, and means for automatically preventing back-flow of fluid 50 from the main turbine supply through the normal exhaust pipe of the cruising turbine.

8. The combination with main and cruising 55 turbine units having connecting means therebetween, of means for operating said units in series or independently of each other without stopping either of said units, including means for supplying steam to said cruising unit, means for directing exhaust steam from said cruising turbine unit into the main 60 turbine unit, and a supplemental exhaust pipe into which steam may be directed when said 65 cruising turbine unit is operating independently of said main unit.

9. The combination with a main turbine 70 and a cruising turbine, turbine auxiliaries

driven by said cruising turbine, and means whereby the cruising and main turbines may be operated entirely independently of each other with respect to the power developed by each, and said latter means being adapted to cause the cruising turbine to transmit its power through the main turbine.

10. The combination with a main turbine and a cruising turbine adapted to transmit its power through the main turbine, of turbine auxiliaries adapted to be driven by the combined power of said turbine, and means whereby said auxiliaries are driven only by the power developed by the cruising turbine when the power developed by the main turbine is between full power and a predetermined power limit below the full power.
